United States Patent Office

Des. 190,549
Patented June 13, 1961

190,549

HAT

Dorothy T. Wieand, 4735 Oakland St., Philadelphia, Pa.

Filed May 18, 1960, Ser. No. 60,626

Term of patent 14 years

(Cl. D3—13)

FIG.1.

FIG. 2.

FIG.3.

FIG. 1 is a plan view of a hat embodying my new design;

FIG. 2 is a view in side elevation of the hat shown in FIG. 1; and

FIG. 3 is a cross sectional view of the hat taken on the line 3—3 of FIG. 1.

I claim:

The ornamental design for a hat, substantially as shown.
